SWITCHING APPARATUS FOR MAGNETIC AMPLIFIERS

John W. Stuart, Monroeville, Pa., assignor to Westinghouse Electric Corporation, East Pittsburgh, Pa., a corporation of Pennsylvania

Filed Aug. 12, 1957, Ser. No. 677,726

3 Claims. (Cl. 323—89)

This invention relates to switching apparatus in general and in particular to switching apparatus utilizing photo-sensitive or radiation sensitive devices and magnetic amplifiers.

In many applications, it is desirable to have switching apparatus which is operative only upon the presence or absence of a condition to be detected externally. The detection of a workpiece at a certain location, the detection of the height of a carton on a conveyor, and the detection of card holes for a computer are examples. It is also desirable that the components making up such a switching apparatus have a long life and require very little or no maintenance.

It is an object of this invention to provide an improved switching apparatus.

It is another object of this invention to provide an improved switching apparatus which conditions its operation upon the detection of the presence or absence of an external condition.

Further objects of this invention will become apparent from the following description when taken in conjunction with the accompanying drawings. In said drawings, for illustrative purposes only, are shown preferred forms of the invention.

Figure 1 is a schematic diagram of an improved switching apparatus embodying the teachings of this invention;

Fig. 2 is a schematic diagram of a second embodiment of the teachings of this invention; and

Fig. 3 is a schematic diagram of a third embodiment of the teachings of this invention.

In the drawings, the manner in which the windings have been wound on the magnetic core members has been denoted by the polarity dot invention. That is, current flowing into a polarity dot end of a winding will drive an inductively associated core toward positive saturation. Current flowing out of the polarity dot end of a winding will drive an inductively associated core away from positive saturation.

Referring to Fig. 1, there is illustrated an improved switching apparatus which illustrates one embodiment of the teachings of this invention. In general, the apparatus illustrated in Fig. 1 comprises a magnetic amplifier 30 and a radiation sensitive device 11. The magnetic amplifier 30 comprises a magnetic core member 31 constructed of a rectangular-looped core material, a gating circuit 2 for driving the magnetic core member 31 to positive saturation and a reset circuit 3 for driving the magnetic core member 31 to negative saturation.

The gating circuit 2 comprises a gating winding 32 inductively disposed on the saturable magnetic core member 31, a gating rectifier 34, a terminal 42 and a rectifier 41 connected in series circuit relationship between a pair of terminals 18 and 19. The terminal 19 is connected to ground. A non-linear resistance circuit 40 comprising the rectifier 41, the terminal 42 and a resistance 43 is connected in series between ground and a negative source of direct current. An alternating-current voltage is to be connected to the terminals 18 and 19.

2

The reset circuit 3 comprises a reset winding 33 inductively disposed on the magnetic core member 31, a reset rectifier 35, a terminal 22 and a rectifier 21 connected in series circuit relationship between a pair of terminals 14 and 15. The terminal 14 is grounded. A non-linear resistance circuit 20 comprising a rectifier 21, the terminal 22 and a resistance 23 is connected between ground and a source of negative direct current. The radiation sensitive device 11 is connected between the input terminal 10 through an isolation rectifier 12 to the terminal 22 of the reset circuit 3. An alternating-current voltage is to be connected to the terminals 14 and 15 and is of the same frequency as the alternating-current voltage to be connected to the terminals 18 and 19. Like instantaneous polarities of the two alternating-current voltages are as noted in Fig. 1.

In operation the gating circuit 2 drives the magnetic core member 31 to substantially positive saturation on a first or gating half-cycle of the alternating-current voltage connected to the terminals 18 and 19. Current flow will be from the terminal 18 through the gating winding 32, the rectifier 34 and the rectifier 41 of the non-linear resistance circuit 40 to the terminal 19. On the same half-cycle there will be no flow of current in the reset circuit 3 because of the blocking action of the rectifier 35.

On the next or reset half-cycle of operation the alternating-current voltage connected to the terminals 14 and 15 will drive the magnetic core member 31 to substantially negative saturation. Current flow will be from the terminal 15 through the reset winding 33, the rectifier 35 and the rectifier 21 of the non-linear resistance circuit 20 to the terminal 14. On this same half-cycle there will be no current flow in the reset circuit 2 because of the blocking action of the rectifier 34. On succeeding half-cycles the magnetic core member 31 will be alternately driven to positive saturation and to negative saturation by the action of the alternating current voltages to be applied to the terminals 18, 19 and 14, 15, respectively. Therefore, all the volt-seconds supplied by the alternating current voltage to be connected to the terminals 18 and 19, on the gating half cycle, will be used in driving the magnetic core member 31 to positive saturation and no output will appear across the rectifier 41 of the non-linear resistance circuit 40.

In order for an output to appear from the gating circuit 2, a voltage must be introduced at the terminal 22 of the reset circuit 3 which will block the resetting action of the reset voltage at the rectifier 35. Whenever this voltage is introduced at the terminal 22, there will be no resetting of the flux in the magnetic core member 31 during the reset half-cycle. On the next succeeding gating half-cycle the magnetic core member 31 will remain at substantially positive saturation and an output will appear across the rectifier 41.

The radiation sensitive device 11 will determine whether or not an input voltage applied on the terminal 10 will also be applied to the terminal 22. As is known to those skilled in the art, a radiation sensitive device, such as a photo-transistor, presents a variable impedance in accordance with the amount of radiation received by the radiation sensitive device. When no radiation is applied to the radiation sensitive device 11, the impedance of the device 11 is of a sufficient magnitude to block the application of the input voltage applied to terminal 10 from the terminal 22 of the reset circuit 3. The application of a radiation input to the radiation sensitive device 11 of a sufficient magnitude to cause the impedance of the radiation sensitive device 11 to drop to a relatively low value, will allow the application of the input voltage applied to the terminal 10 to also be applied to the terminal 22, thereby blocking the reset half-cycle of the magnetic amplifier 30.

The non-linear resistance circuits 40 and 20 are well-known to those skilled in the art and serve the following functions. First, a non-linear resistance circuit presents a low impedance in series with the voltage in the reset circuit 3 in order to reset the magnetic core member completely with the reset voltage when an input or blocking voltage is absent. Secondly, a non-linear resistance circuit presents a high impedance to provide least loading of a proceeding or driving stage when an input signal is present. The same reasoning applies when using a non-linear resistance circuit in the gating circuit 2. It is to be noted that an impedance may be used in place of a non-linear resistance circuit but the proper value of this impedance can only be a compromise between the two conflicting requirements noted above. The negative direct current sources may be pulsating, half-wave sources of the same frequency as the alternating-current voltages applied to the gating circuit 2 and the reset circuit and properly phased to allow reverse current flow through the non-linear resistance circuit rectifiers on the gating and reset half-cycles.

Summarizing in brief, the apparatus illustrated in Fig. 1 has an output from its gating circuit 2 only when there is an input voltage of the proper phase and magnitude present at the terminal 10 and a radiation input of sufficient magnitude present on the radiation sensitive device 11. If either the radiation or the voltage input is not present, then there will be no output from the apparatus illustrated in Fig. 1. If the input signal to be applied to be applied to the terminal 10 is either an alternating current or pulsating direct current, it must have the proper phase and magnitude to block the reset voltage. However, a pure direct current signal may be used without regard to phasing.

Referring to Fig. 2, there is illustrated another embodiment of the teachings of this invention, in which like components of Figs. 1 and 2 have been given the same reference characters. The main distinction between the apparatus illustrated in Figs. 1 and 2 is that in Fig. 2 a different type of reset circuit 4 has been substituted. The reset circuit 4 comprises the reset winding 33 and a reset rectifier 36 extending from the isolation rectifier 12 to the terminal 22 of the non-linear resistance circuit 20.

In operation the apparatus illustrated in Fig. 2 is very similar to the apparatus illustrated in Fig. 1, only the operation of the reset circuit 4 being different. The gating circuit 2 still functions to drive the magnetic core member 31 to positive saturation on the gating half-cycle of the alternating-current voltage to be connected to the terminals 18 and 19. However, the reset circuit 4 functions to drive the magnetic core member 31 to substantially negative saturation only when an input voltage of the proper phase and magnitude is applied to the terminal 10, and then only when the proper radiation input is applied to the radiation sensitive device 11. As hereinbefore described, the phasing of the input signal at the terminal 10 may be disregarded if the pure direct current input is used. If the two above conditions are met, then on the reset half-cycle current will flow from the terminal 10 through the radiation sensitive device 11, the isolation rectifier 12, the reset winding 33 and the rectifier 36 to the terminal 22 of the non-linear resistance circuit 20.

Summarizing in brief the operation of the apparatus illustrated in Fig. 2, it is noted that there is an output from the apparatus at all times unless both an input voltage of the proper phase and magnitude is present at the terminal 10 and a radiation input of the proper magnitude is present to the radiation sensitive device 11. If either of these two inputs are absent, there will be an output from the gating circuit 2 across the rectifier 41 of the non-linear resistance circuit 40.

Referring to Fig. 3, there is illustrated another embodiment of the teachings of this invention, in which like components of Figs. 2 and 3 have been given the same reference characters. The main distinction between the ap-

paratus illustrated in Figs. 2 and 3 is that in Fig. 3 another complete circuit performing the same function as the apparatus illustrated in Fig. 2 has been connected with a circuit identical to that in Fig. 2 to perform a bi-stable function. There has been added an additional magnetic amplifier 80 and an additional radiation sensitive device 61. The magnetic amplifier 80 comprises a magnetic core member 81, constructed of a rectangular loop core material, a gating circuit 6 for driving the magnetic core member 81 to positive saturation and a reset circuit 8 for driving the magnetic core member 81 to negative saturation when a control signal is applied thereto.

The gating circuit 6 comprises a gating winding 82 inductively disposed on the saturable magnetic core member 81, a gating rectifier 84, a terminal 92 and a rectifier 91 connected in series circuit relationship between a pair of terminals 68 and 69. The terminal 69 is connected to ground. A non-linear resistance circuit 90 comprising the rectifier 91, the terminal 92 and a resistance 93 is connected in series between ground and a negative source of direct current. An alternating-current voltage is to be connected to the terminals 68 and 69.

The reset circuit 8 comprises a reset winding 83 inductively disposed on the core 81 and a reset rectifier 86 connected in series circuit relationship between an input isolating rectifier 62 and a terminal 72. A non-linear resistance circuit 70 comprising a rectifier 71, the terminal 72 and a resistance 73 is serially connected between ground and a negative source of direct current. The radiation sensitive device 61 is connected between an input terminal 60 and the isolation rectifier 62.

The outputs of the magnetic amplifiers 30 and 80 from the terminals 42 and 92, respectively, have been connected to an output terminal 50. A feedback circuit connects the output terminal 50 to the terminals 103 and 101 of the reset circuits 4 and 8 of the magnetic amplifiers 30 and 80, respectively, through the rectifiers 104 and 102, respectively.

The operation of the additional apparatus, the magnetic amplifier 80 and the radiation sensitive device 61, is similar to the operation of the apparatus illustrated in Fig. 2. The distinction in operation is that the alternating-current voltage to be applied to the terminals 68 and 69 is of the same frequency as the alternating-current voltage to be applied to terminals 18 and 19, but is of the opposite phase as denoted by the polarity markings in Fig. 3.

The operation of the apparatus illustrated in Fig. 3 may be described as follows. Assume that the magnetic amplifier 30 is producing an output. A portion of this output is fed back into the rectifier at 102 to the terminal 101 and resets the magnetic amplifier 80 through the action of the reset circuit 8. A half-cycle later, therefore, the magnetic amplifier 80 will produce no output at the terminal 92. There will be then no output fed back from the terminal 92 from the rectifier 104 to the reset circuit 4 of the magnetic amplifier 30. Thus, the magnetic amplifier 30 on a next half-cycle will again have an output at the terminal 42 and thus at the terminal 50 and the cycle will repeat. This stable output condition is self-sustaining and the output voltage will be a half-wave voltage in phase with the gating voltage applied to the terminals 18 and 19 of the gating circuit 2 of the magnetic amplifier 30.

A voltage applied to the reset circuit 4, of the proper phase and magnitude, will reset the magnetic core member 31 and the magnetic amplifier 30. A half-cycle later no output will appear at the terminal 42 of the gating circuit 2 of the magnetic amplifier 30. Since there is no output on this half-cycle at the terminal 42, there will be no resetting of the magnetic core member 81 of the magnetic amplifier 80 by the impression of a voltage on a reset circuit 8 through the feedback rectifier 102. The magnetic core member 81 will not be reset and a half-cycle later an output will appear at the terminal 92 of the gating circuit 6 of the magnetic amplifier 80. This

output at the terminal 92 will be substantially 180° out of phase with the previous output which had appeared at the terminal 42. The output from the magnetic amplifier 80 will reset the magnetic core member 31 of the magnetic amplifier 30 by being fed back through the feedback rectifier 104 to the reset circuit 4. The magnetic core member 31 will be reset and on the next half-cycle again no output will appear at the terminal 42. Even though the voltage applied to the reset circuit 4 of the magnetic amplifier 30 is removed, the output will remain at the terminal 92, and thus at the terminal 50 having an opposite phase to the output of the prior stable condition.

The output at the terminal 50 of the apparatus illustrated in Fig. 3 may be shifted back to the original phase by introducing a voltage of the proper phase and magnitude at the terminal 101 of the reset circuit 8 of the magnetic amplifier 80.

The input voltage to be applied to the reset circuits 4 and 8 will be applied at the input terminals 10 and 60, respectively. As described hereinbefore, the radiation sensitive devices 11 and 61 will continue to regulate the application of the input voltages to the reset circuits 4 and 8 depending upon whether or not they are receiving radiation inputs of the proper value to lower their impedance accordingly.

Summarizing in brief the operation of the apparatus illustrated in Fig. 3, we find that there is an output at the terminal 50 of one phase that may be shifted to the opposite phase by the application of an input voltage of the proper phase and magnitude to the reset circuit of the magnetic amplifier producing the output at the terminal 50. This input voltage, however, will be ineffective to cause a change in the output at the terminal 50 unless the radiation sensitive device associated with the respective input terminal is receiving a radiation input of sufficient magnitude to lower the impedance of the radiation sensitive device to a relatively low level.

In conclusion, it is brought out that while the illustrated examples constitute a specific embodiment of my invention, I do not limit myself to the exact details shown, since modification of the same may be varied without departing from the spirit of this invention.

I claim as my invention:

1. In a switching apparatus, in combination, a radiation sensitive device and a magnetic amplifier, said magnetic amplifier comprising a magnetic core member, a gating circuit including a gating winding inductively disposed on said magnetic core member and a gating rectifier, means for applying a first alternating voltage to said gating circuit, said gating circuit being operative so that on one half-cycle of said first alternating voltage substantially all of said voltage is absorbed in driving said magnetic core member from negative to positive saturation and on the other half-cycle of said first alternating voltage said gating rectifier blocks the flow of current through said gating winding, a reset circuit including a

reset winding inductively disposed on said magnetic core member and a reset rectifier, said reset circuit being adapted to drive said magnetic core member from positive to negative saturation only upon the application of an input signal to said reset circuit, said radiation sensitive device being connected to said reset circuit to prevent the application of an input signal to said reset circuit except when said radiation sensitive device receives a radiation input.

10. 2. Switching apparatus for initiating a first series of pulses in response to a coincidentally applied first electrical input signal and first radiation input and initiating a second series of pulses substantially 180° out of phase with said first series of pulses in response to a coincidentally applied second electrical input signal and second radiation input comprising a pair of magnetic amplifiers and a radiation sensitive device for each of said magnetic amplifiers, means for connecting an alternating voltage in series with a gating winding of each of said magnetic amplifiers, means responsive to said first electrical input signal for desaturating a magnetic core member of one of said pair of magnetic amplifiers only upon the application of said first radiation input, and means responsive to said second electrical signal for desaturating a magnetic core member of the other of said pair of magnetic amplifiers only upon the application of said second radiation input.

3. Switching apparatus for initiating a first series of pulses in response to a coincidentally applied first electrical input signal and first radiation input and initiating a second series of pulses substantially 180° out of phase with said first series of pulses in response to a coincidentally applied second electrical input signal and second radiation input comprising a pair of magnetic amplifiers and a radiation sensitive device for each of said magnetic amplifiers, means for connecting an alternating voltage in series with a gating winding of each of said magnetic amplifier means, means responsive to said first electrical input signal for desaturating a magnetic core member of one of said pair of magnetic amplifiers only upon the application of said first radiation input, and means responsive to said second electrical signal for desaturating a magnetic core member of the other of said pair of magnetic amplifiers only upon the application of said second radiation input, and means for feeding back the output of each of said pair of magnetic amplifiers to means for desaturating the other of said pair of magnetic amplifiers.
